UNITED STATES PATENT OFFICE.

ROBERT KÜHN, OF BERLIN, GERMANY.

MASSAGING APPARATUS WITH REVOLVING ECCENTRIC SECTIONS.

Application filed February 8, 1921. Serial No. 443,482.

(GRANTED UNDER THE PROVISIONS OF THE ACT OF MARCH 3, 1921, 41 STAT. L., 1313.)

To all whom it may concern:

Be it known that I, ROBERT KÜHN, a citizen of the German Republic, residing at Berlin, Germany, have invented certain new and useful Improvements in Massaging Apparatus with Revolving Eccentric Sections (for which I have filed an application in Germany, Mar. 24, 1914), of which the following is a specification.

There have already become known apparatuses for massage of the kind in which eccentric massaging bodies are arranged upon a flexible shaft at determined distances apart. With such massaging apparatus it is only possible to massage at certain points, the flexibility of the shaft which carries the massaging bodies, preventing in any cases a favourable action as the massaging bodies can yield instead of acting effectively upon the human body.

This invention has for its object to use a massaging apparatus for surface massaging in utilizing the well known eccentric sections as massaging bodies. These eccentric sections are mounted, according to the invention, so that they are in close contact with one another and form together a continuous rigid massaging shaft, whose eccentric bodies produce a massaging action

successively along the entire length of the shaft. If this revolving shaft is being moved over a part of the human body which has to be massaged, the entire surface of the body situated below the shaft is massaged at the same time. The eccentric sections of the massaging shaft can all be cut out of one shaft or they can consist of separate sections which are tightly mounted upon a rigid shaft.

In order that the invention may be clearly understood, I shall proceed to describe the same with reference to the example of construction shown in the accompanying drawing.

The massage apparatus consists of a U-shaped holder *c* in which the rigid shaft *n* of the massaging apparatus is mounted so that it can be connected with the flexible shaft *b*. Upon said shaft *n* a hollow rod

h is mounted which has been turned on the lathe so that a number of adjacent sections of different eccentricity are produced. The several sections of said rod *h* are all of the same diameter, but they have been turned in such a manner that the centers of the sections are displaced in different directions the one with regard to the others. Consequently when the rod *h* revolves the parts of the rod which possess the greatest eccentricity will act successively upon the point of the human body which has to be massaged, and as said eccentric sections are distributed over the entire length of said rod, the massaging action upon the corresponding point of the human body will take place successively along the entire length of said shaft at every revolution of the same. The massaging action is based upon the force of the strokes which depends on the amplitude of the eccentricity of the sections of the rod *h* and it may be called "surface massage" as with every revolution of the shaft *n* the numerous sections of the rod *h* act simultaneously along the entire length of the shaft *n*.

The above described effect could also be obtained if the rod *h* was composed of a certain number of separate sections mounted on the shaft *n* so that they are in close contact with one another and fixed upon said shaft *n*. The rod *h* or the eccentric sections of the same are preferably made from wood.

I claim:—

1. An improved massaging apparatus for surface massage comprising in combination with a U-shaped holder, a rigid shaft revolvably mounted in said holder, a flexible driving shaft connected with said rigid shaft, a hollow rod of wood upon said rigid shaft, said rod consisting of a number of sections of different eccentricity, substantially as described and shown and for the purpose set forth.

2. An improved massaging apparatus for surface massage comprising in combination with a U-shaped holder, a rigid shaft revolvably mounted in said holder, a flexible

driving shaft connected with said rigid shaft, and perforated sections of wood which possess different eccentricity mounted upon said rigid shaft so that they are in close contact the one with the other, substantially as described and shown and for the purpose set forth.

In testimony whereof I affix my signature in presence of two witnesses.

ROBERT KÜHN.
